CLAIM

The ornamental design for a decorative fire table, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a decorative fire table showing the top, front, and right sides of the new design. FIG. 2 is a perspective view of a decorative fire table showing the top, front, and right sides in another environment of use.

FIG. 3 is a perspective view showing the top, rear, and left sides of the design shown in FIG. 1.

FIG. 4 is a perspective view showing the top and the rear sides of the design shown in FIG. 1.

FIG. 5 is a perspective view showing the top and left sides of the design shown in FIG. 1.

FIG. 6 is a perspective view showing the top and rear sides of the design shown in FIG. 1 in another environment of use; and,

FIG. 7 is a perspective view showing the top, rear, and left sides of the design shown in FIG. 1 in another environment of use.

The bottom is flat and devoid of surface ornamentation.
